(57) **CLAIM**

The ornamental design for a clamp assembly for solar panel assemblies, as shown and described.

DESCRIPTION

FIG. 1 is a first perspective view of a clamp assembly for solar panel assemblies;

FIG. 2 is a second perspective view thereof;

FIG. 3 is a front view thereof;

FIG. 4 is a rear view thereof;

FIG. 5 is a top view thereof;

FIG. 6 is a bottom view thereof;

FIG. 7 is a left-side view thereof;

FIG. 8 is an exploded perspective view thereof;

FIG. 9 is the first perspective view thereof, shown with a cable management clip;

FIG. 10 is the second perspective view thereof, shown with an L-bracket; and,

FIG. 11 is the front view thereof, shown with a standing seam roof.

Subject matter shown in broken lines is environmental and forms no part of the claimed design.
